United States Patent Office

Des. 203,198

Patented Dec. 14, 1965

203,198

TABLE OR SIMILAR ARTICLE

Moses Richard Schultz, Barto, Pa., assignor to Knoll Associates Inc., New York, N.Y., a corporation of New York

Filed Dec. 6, 1963, Ser. No. 77,697

Term of patent 14 years

(Cl. D33—14)

Fig. 2.

Fig. 1.

FIG. 1 is a perspective view of a table showing my design, the end and side not shown being the same in appearance as the end and side shown.

FIG. 2 is an enlarged top plan view of the table with portions thereof broken away whereby to illustrate the top in greater detail.

The dominant features of my design reside in those portions shown in full lines in the drawings.

The furniture top is characterized by stretchers which are set into the surface of the top and extend parallel to the edges of the top, said stretchers being disposed so that they are spaced from the portions of the top adjacent thereto.

I claim:

The ornamental design for a table or similar article,
